UNITED STATES PATENT OFFICE

156,262

DESIGN FOR AN ELECTRONIC CALCULATING MACHINE

Thomas O. Mehan, Park Ridge, Ill., assignor to
Victor Adding Machine Co., Chicago, Ill., a corporation of Illinois

Application September 29, 1947, Serial No. 141,647

Term of patent 14 years

(Cl. D64—11)

To all whom it may concern:

Be it known that I, Thomas O. Mehan, a citizen of the United States, residing at Park Ridge, in the county of Cook and State of Illinois, have invented a new, original, and ornamental Design for an Electronic Calculating Machine, of which the following is a specification, reference being had to the accompanying drawings forming part thereof.

Fig. 1 is a perspective view of an electronic calculating machine, showing my new design; and

Fig. 2 is a front elevational view thereof.

I claim:

The ornamental design for an electronic calculating machine, substantially as shown.
THOMAS O. MEHAN.
